(57) **CLAIM**

The ornamental design for a wood splitting machine, as shown and described.

DESCRIPTION

FIG. 1 is a front, right, top perspective view of a wood splitting machine showing our new design;

FIG. 2 is a back, right, bottom perspective view thereof;

FIG. 3 is a front view thereof;

FIG. 4 is a back view thereof;

FIG. 5 is a right view thereof;

FIG. 6 is a left view thereof;

FIG. 7 is a top view thereof;

FIG. 8 is a bottom view thereof; and,

FIG. 9 is a vertical placement use state diagram.

The broken lines in the figures illustrate the portions of the wood splitting machine that form no part of the claimed design.

1 Claim, 9 Drawing Sheets
